UNITED STATES PATENT OFFICE.

JOHN T. LOMAS, OF NEW YORK, N. Y.

GEOGRAPHICAL EDUCATIONAL GAME APPARATUS.

Application filed July 22, 1926. Serial No. 124,258.

This invention relates to the class of game apparatuses, and has especial reference to game apparatuses characterized by educational features.

5 The principal object of the present invention is the provision of an educational game apparatus which is instructive in geography to the persons using the apparatus, and which incidentally gives some of 10 the pleasurable benefits derived from traveling about from place to place; and in the playing with which, in accordance with rules provided, certain questions will arise to be answered in the progress of the game. 15 Another object of the present invention is the provision in a game apparatus of a novel form of spinning device.

With the foregoing, other objects of the invention will appear from the embodiment 20 of the invention which by way of example is described in the following specification and illustrated in the accompanying drawings, in which

Figure 1 is a plan view of a spinner forming a part of the apparatus of the present invention.

Fig. 2 is a view similar to Fig. 1, showing the slide of the spinner moved to its other position.

30 Fig. 3 is a sectional view on the line 3—3 of Fig. 1.

Fig. 4 is a view of the map forming a part of the apparatus.

Fig. 5 is a perspective view of one of the 35 game pieces in the form of an airplane.

Fig. 6 is a perspective view of another type of game piece.

Fig. 7 is a fragmentary plan of a modified form of spinning device.

40 Fig. 8 is a view similar to Fig. 7 showing the hinged indicia bearing member in its other position.

Fig. 9 is a sectional view taken on the line 9—9 of Fig. 7.

45 Generally stated, the game apparatus of the present invention comprises a map 10, a spinning device 11, and tokens or game pieces 12 which are moved with respect to the map by the persons playing the game.

50 More specifically stated, the parts consist of and are used in a manner presently to be described. The map 10 may be of any section of the world, and in fact may be a map of the world. In the present instance 55 the map 10 is a map of Africa and some of the adjacent countries, and will be printed

on a suitable plate. The map 10 will include among the principal cities and bodies of water properly named, lines 13 denoting longitude, and lines 14 denoting latitude. 60 Certain of the lines of longitude 13 are indicated by accurate designations 15 of degrees from the meridian, whereas, certain of the lines 14 are indicated by accurate designations 16 of degrees from the Equator. 65

The spinning device shown in Figs. 1 and 2 includes top and bottom members 17 and 18, the top member 17 being slidably associated with the bottom member 18. The top member 17 has imprinted on one face 70 thereof a dial 19 subdivided into sectors 20, 21 and 22. The sectors 20 are of a distinctive color and each has indicia 24 therein denoting "degrees". The sectors 21 each have indicia similar to that of the sectors 75 20. The sectors 22 have indicia 25 as follows: "Forced down", "Blown 4° N.", "Blown 4° S.", "Blown 4° E.", "Blown 4° W." The sectors 22 are distinctively colored. A pointer 26 is associated with the 80 dial 19 and is capable of being spun with respect to the dial. The bottom member 18 is provided with a marginal portion 27 which guides the top member 17 for sliding movement, and limits its movement in opposite directions. At one end of the bottom member 18 on one face thereof is imprinted indicia 28 which is complementary to the indicia of the sectors 20, 21. The opposite end of the bottom member 18 on the same face having the indicia 28, is indicia 29 which is complementary to the indicia of the sectors 20, 21. 90

The token or game piece used is one which simulates an airplane. As shown in Fig. 5 95 the game piece consists of a member 30 in the form of a pointer which has attached thereto by a supporting member 31, a member 32 of a form to simulate an airplane. In lieu of the type of game piece shown in Fig. 5, a type of game piece such as the one shown in Fig. 6 may be provided. In the type of game piece shown in Fig. 6 a pointer 33 has secured thereto a member 34 formed to simulate an airplane. 100 105

Figs. 7, 8 and 9 illustrate a modified form of spinning device having the same general characteristics of the device 11. The modified form of device 35 consists of a plate 36 having a dial 37 similar to the dial 19 printed thereon, and which will have associated therewith a pointer. One end of the 110

plate has hingedly connected thereto a member 38; the member being hinged in small bearing members 39 on pintles 40, one of which has a knurled knob 41 for turning the member 38 from one position to the other to cover and uncover certain portions of the face of one end of the plate 36. One side of the member 38 has indicia 42 which corresponds to the indicia 29 of the device 11, whereas the face portion of the end of the plate having the member 38 has indicia 43 which corresponds to the indicia 28 of the device 11. The arrangement is such that in one position of the member 38 the indicia 43 will be covered as shown in Fig. 7 and when the member 38 is in its other position the indicia 38 will not be visible while the indicia 43 will be uncovered, as shown in Fig. 8.

20 In playing the game which will be known as "the educational aero race" certain rules will govern as follows:

1. Players first decide upon their starting and finishing points.

25 2. Each player in turn will take one spin and move as directed by arrow.

3. In the event of an airplane being forced down the owner will have one minute in which to state one fact or answer one question relating to the country over which he was flying.

4. This player may choose whether he shall state a fact or answer a question.

35 5. Should the player fail to make a correct statement or to correctly answer the question, he will remain upon the particular point negotiated until all other players have taken their spin.

40 6. The player wins who first passes directly over the finishing point.

A reference book giving certain data relating to the countries appearing in the map and the cities, and divers other information regarding the people and products for which the different localities are noted will be furnished, to add to the interest of the game and to be in accordance with certain features of the game for governing the moves of the game pieces.

50 In playing the game the player uses the spinning device and determines whether the pieces are to be moved with respect to the longitude or latitude by exposing the particular indicia 28 or 29. Assuming that a 55 player moves the member 17 to uncover the indicia 28, it will then be understood that the player has decided to move the game piece east or west in accordance with the indicia appearing in the sector at which the pointer 26 stops which will be a certain number of degrees east or west, which will bring the game piece at a certain degree of latitude or longitude. The pointer may stop over one of the sectors 21 or 22 and a corresponding move will be made in the event that it

is consistent with the particular indicia 28 or 29 exposed at this particular time. If the pointer 26 stops over the section having the indicia "Forced down" it will be necessary for the player to adhere to rules 3 and 4 hereinbefore set forth. If the top member 17 is moved to the position shown in Fig. 2, the indicia 28 will be covered and the indicia 29 will be exposed so that a player may move the game piece with respect to latitude or longitude. In the event that the pointer 26 stops over one of the sectors 20 a move will be made in accordance with the indicia appearing in the particular sector. In moving each game piece 12 the pointed end will be brought to the particular degree of longitude or latitude as the case may be. The spinning device shown in Figs. 7, 8 and 9, as before stated, has the same general features as the device shown in Figs. 1, 2 and 3 and may be used in conjunction with the map 10 and game pieces 12 by simply moving the member 38 from one position to another at the will of the player.

It is to be understood that the invention is not restricted to the precise features and details of construction shown and described, as alterations and modifications may be resorted to whenever it is deemed necessary or desirable in accordance with the scope of the appended claims.

I claim:

1. A game device comprising a plate, indicia on each end portion of said plate, a slide slidable with respect to said plate to alternately uncover said end portions, said slide subdivided into sectors, indicia in each sector complementary to the indicia on said end portions to denote different "distances", and a pointer operatively carried by said slide to be spun with respect to said sectors to indicate a particular "distance".

2. A game device comprising a plate, indicia on each end portion of said plate, a slide slidable with respect to said plate to alternately uncover said end portions, said slide subdivided into sectors, indicia in each sector complementary to the indicia on said end portion to denote different "distances", a pointer operatively carried by said slide to be spun with respect to said sectors to indicate a particular "distance", and means limiting the sliding movement of the slide in opposite directions.

3. A spinner for a geographical educational game apparatus, said spinner comprising top and bottom members, the top member carried by and movable with respect to the bottom member, the top member being smaller than the bottom member to permit opposite end portions of the bottom member to be alternately covered and uncovered, said members bearing complementary indicia, the indicia on the bottom

member being covered and uncovered as the top member is moved with respect to the bottom member, and a pointer on the top member capable of being spun with respect to the indicia thereon, as and for the purpose specified.

4. A game device comprising a plate, distinctively colored sections on each end portion of one face of the plate, indicia on each end portion, a member movable with respect to said plate to cover one end portion of the plate to render its colored sections and indicia invisible while uncovering the

other end portion of the plate to render its colored sections and indicia visible, said member subdivided into groups of distinctively colored sectors, one group of sectors corresponding in color to the color of one of the sections of each end portion, indicia in each of said sectors complementary to the indicia on each of said end portions of the plate, and a pointer on said member capable of being spun with respect to said sectors.

JOHN T. LOMAS.
